UNITED STATES PATENT OFFICE.

GUSTAV VOGT, OF LIMOGES, FRANCE.

DESIGN FOR A CUSPIDOR.

SPECIFICATION forming part of Design No. 14,483, dated December 11, 1883.

Application filed October 2, 1883. Term of patent 7 years. Patented in France December 26, 1882, No. 120.

To all whom it may concern:

Be it known that I, GUSTAV VOGT, of Limoges, in the Republic of France, have invented 5 which the following is a full, clear, and exact description, reference being had to the accompanying drawings, making part of this specification, in which—

Figure 1 is a side view of a cuspidor made 10 according to my design, and Fig. 2 is a plan of the same.

Similar letters of reference indicate corresponding parts.

This design relates to cuspidors; and it consists of a cuspidor composed of a triangular mouth having rounded-off corners and flaring sides, the latter being slightly inwardly curved 15 near the corners, and having an outward swell or bulge at the center, and of a triangular body, the lower part of which swells outwardly 20 from the base and the upper part inwardly toward the neck, the corners being rounded off and the sides slightly inwardly curved near the corners and outwardly bulged at the center. 25

The mouth A of the cuspidor is made triangular in its general contour and flaring inwardly toward the contracted neck. The sides a are slightly drawn in or concaved near the 30 corners and convexly bulged at the center, so as to form a graceful curve between the corners of the cuspidor. The corners B are round- 35 ed off, so as to complete the curved contour

of the mouth. The body C of the cuspidor is also made triangular in its general contour, 35 with convexly-bulging sides E, and flaring from its base in an upward and outward direction for about one-third of its height, and then inwardly and upwardly to the contracted part of the neck of the cuspidor. The sides 40 of the body C correspond to the convexly-bulging contour of the mouth, the angles or corners E being also rounded off, so that the cuspidor presents an elegant and graceful appearance. 45

Having thus described my invention, I claim as new and desire to secure by Letters Patent—

The design for a cuspidor, composed of a triangular mouth having rounded-off corners and flaring sides, the latter having a slight inward curve near the corners, and an outward swell or bulge at the center, and of a triangular body, the lower part of which swells outwardly 50 from the base and the upper part inwardly toward the neck, said body having 55 rounded-off corners and sides which are slightly inwardly curved near the corners and outwardly bulged at the center, as shown and described.

In testimony that I claim the foregoing as 60 my invention I have signed it this 31st day of August, 1883.

GUSTAV VOGT.
